To all whom it may concern:

Be it known that I, EDWARD J. Fig. 1 is a plan view of the game device showing my new design.

Fig. 2 is a partial side elevation the upper portion being a vertical cross-section taken through the center of the game device. The lower right-hand corner is broken away but the device is symmetrical so that the portion not shown is similar to the portion shown.

I claim:

The ornamental design for a game device as shown and described.

EDWARD J. BRADY.
